MEANS FOR SUSPENDING AND SEALING
CASINGSHerbert Allen and Madden T. Works, Houston,
Tex., assignors to Cameron Iron Works, Inc.,
Houston, Tex., a corporation of Texas

Application December 4, 1948, Serial No. 63,497

5 Claims. (Cl. 285—22)

1

This invention relates to improved means for suspending and sealing a casing or other pipe in a casing head.

One object of this invention is to provide a novel structure for hanging a string of casing at any point in its length within a casing head and sealing the casing to the casing head.

Another object of this invention is to provide a slip bowl having downwardly tapered outer and inner faces for respectively engaging the tapered bowl portion of a casing head and supporting a series of wedge shaped slip segments by which the casing or other pipe is engaged.

A further object of this invention is to provide a slip bowl which in addition to supporting the slip segments forms a part of the means for sealing the casing within the casing head.

A further object of this invention is to provide slip suspending means for casing or other pipe wherein a divided ring of slip segments are preliminarily attached to a slip bowl by threaded members and maintained in widely spaced raised positions so as to facilitate assembly of the means upon the pipe.

A further object of the invention is to provide a casing suspension and seal apparatus for a casing head which can be assembled on the inner casing, lower through pressure control equipment into the casing head, engage and support the inner casing, and close the annular space against upward pressure.

Still another object of this invention is to provide a casing suspension and seal device which can be introduced through blowout preventer equipment, or the like, to a position in a well head to support the inner casing and provide an initial closure to permit removal of the control equipment, after which a second seal may be established.

Other objects and advantages will be apparent from the following description taken in connection with the accompanying drawing illustrating a presently preferred embodiment of this invention.

In the drawings:

The single figure is a vertical sectional view showing a string of pipe suspended in its supporting structure with suitable seals in place thereabout.

Referring now to the drawing, the numeral 10 designates a casing head, supported conventionally upon the surface casing (not shown) or other pipe, and provided centrally with an inclined bowl portion 11 below a cylindrical bore portion 12 of relatively large diameter. The upper end of the casing head 10 is formed with a lateral flange 13 provided with a plurality of openings

2

through which it may be bolted to the flange 14 of an upper well equipment member, such as another casing head, blowout preventer valve, or the like. The facing sides of flanges 13 and 14 have registering grooves to receive the metal seal ring 15 which forms a fluid tight seal between them.

A string of well casing or other pipe is suspended from casing head 10 by the downwardly tapering wedge shaped slip segments 17 whose inner faces are toothed to engage and support the casing 16 and whose outer tapering faces engage the downwardly tapering inner periphery of the slip bowl 18. The lower portion of the outer periphery of the slip bowl 18 is downwardly tapered to fit the tapered bowl portion 11 of the casing head while the upper portion of its outer periphery is shaped as a cylinder and of a diameter to fit within the cylindrical portion 12 of the casing head. The upper portion 18a of the slip bowl is also crowned on its upper face to aid in the compression of the resilient packing ring 19 superposed thereon, serving as the lower gland ring in the main sealing or pack-off assembly in conjunction with packing ring 19 and the upper gland ring 20, which has a depending oppositely crowned lower surface for aid in properly compressing and expanding the resilient packing ring 19.

The means for manually compressing and expanding packing ring 19 is herein shown as comprising a series of headed screws 21 having their heads countersunk into openings in upper gland ring 20 and provided with non-circular sockets 35 for the reception of a suitable wrench. The shanks of screws 21 extend through aligned openings in the upper gland ring 20 and packing ring 19 into threaded apertures in the lower gland ring, herein shown as the upper portion 18a of the slip bowl 18. Screws 21 are tightened down progressively to compress the resilient packing ring 19 and expand it transversely of the axis of the casing to form seals between the casing 16 and the cylindrical portion 12 of the casing head.

Additional seals may also be provided between the slip bowl 18 and both the casing 16 and the casing head, or either of them, in order to form an initial seal between the casing head and casing before the screws 21 are tightened. In the illustrated embodiment, a seal is provided between the tapered outer periphery of the slip bowl 18 and the bowl portion 11 of the casing head by providing an annular recess 18b in the slip bowl for the reception of suitable resilient packing ring 22, as, for example, a conventional O-ring. As the slip bowl 18 is lowered into en-

gagement with the bowl portion 11 of the casing head, packing ring 22 will be compressed to form a seal therebetween. Between the casing 16 and the upper portion 18a of the slip bowl is arranged a second seal 23, herein shown as a lip seal of suitable resilient material fitting within a conformably shaped annular recess 18c in the lower corner of the inner peripheral wall of the upper portion 18a of the slip bowl. The lip ring 23 is preferably formed with a divided skirt portion arranged to be spread by fluid under pressure from the well into sealing engagement with the casing 16.

Preparatory to mounting the slip bowl and slip segments as an assembly around casing 16, each slip segment 17 is secured to the lower tapered portion of slip bowl 18 in raised and retracted position by a suitable screw (not shown) extending through a suitable aperture 18d in the slip bowl and threaded into a then aligned threaded aperture 17a in the slip segment. The several slip segments 17 may also be maintained all on the same level at all times by an outwardly expanding split resilient snap ring 25 arranged in recesses 17b formed in the toothed inner faces of the slip segments. With the slip segments held retracted by the bolts as described, the casing may be readily manipulated to the point where it is to be hung. Then said bolts are removed, permitting the slip segments to advance with the slip bowl 18 into contact with the casing and the entire assembly is lowered into the casing head 10 until the slip bowl 18 seats in the tapered bowl 11 of the casing head. Thereupon casing 16 is properly secured in suspended relation from the casing head. The flexibility of the resilient snap ring 25 is sufficient to permit movements of the several slip segments 17 relatively to each other out of their original aligned positions while serving to aid in keeping them on a level with each other. At this point it will be noted that an initial seal will have been formed between the casing and casing head by means of rings 22 and 23 to prevent blowout of pressure within the annulus about the casing.

The suspension and seal assembly are of such outside diameter as will pass downwardly through the bore of conventional blowout preventer and control equipment which is usually used during the drilling and casing setting operations.

After the casing is set and the seals are installed and tested, if desired, the control equipment may be replaced with other equipment, such as a tubing head, having a reduced bore as illustrated in the drawing.

After the slip segments 17 and slip bowl 18 have reached their positions with the casing 16 suspended therein, packing ring 19 is advanced over the upper end of the casing to rest on the crowned upper face of slip bowl portion 18a and the upper gland ring 20 similarly advanced to rest on packing ring 19. Headed screws 21 are then threaded into position and progressively tightened down to expand packing ring 19 into sealing engagement with both the casing 16 and the cylindrical bore portion 12 of the casing head. The seals may be tested, if desired, by appropriate testing apparatus before the well is completed.

While the illustrated embodiment is believed to adequately fulfill the object and advantages herein stated, it is to be understood that this invention is susceptible to modification and variation within the scope of the subjoined claims.

Having described our invention, we claim:

1. In combination with a casing head having

a tapered bowl portion and a cylindrical bore portion thereabove, means for suspending and sealing a string of casing therein comprising a slip bowl having inner and outer tapered walls and adapted to fit within the bowl portion of the casing head, a series of slip segments arranged to cooperate with the inner tapered wall of said slip bowl in suspending the casing, removable means for preliminarily supporting said slip segments in raised positions within said slip bowl, and means for sealing between the casing and casing head above said slip ring comprising a lower gland ring carried by said slip bowl, a resilient packing ring, and an upper gland ring, headed screws threaded into one of said gland rings being arranged to compress said packing ring and expand it into sealing engagement with both the casing and casing head.

2. In combination with a casing head having a tapered bowl portion and a cylindrical bore portion thereabove, means for suspending and sealing a string of casing therein comprising a slip bowl having inner and outer tapered walls and adapted to fit within the bowl portion of the casing head, a series of slip segments arranged to cooperate with the inner tapered wall of said slip bowl in suspending the casing, means for preliminarily supporting said slip segments in raised positions within said slip bowl, packing means carried by the slip bowl for sealing its outer tapered wall against the bowl portion, and packing means carried by the slip bowl for sealing its inner wall against the casing, and means for sealing between the casing and casing head above said slip segments comprising a lower gland ring carried by said slip bowl, a resilient packing ring, and an upper gland ring, headed screws threaded into one of said gland rings being arranged to compress said packing ring and expand it into sealing engagement with both the casing and casing head.

3. A well casing support and packoff assembly comprising a slip bowl adapted to be received by a casing head having a tapered seat with a cylindrical portion thereabove, the upper portion of the slip bowl being annular and of a dimension to substantially fill the space between a well casing and a casing head, the upper annular surface of the slip bowl providing a seat, a packing ring on said seat, a packing gland on said ring, and connection means between said gland and slip bowl which may be tightened to advance the gland toward the slip bowl to expand the packing ring radially inwardly and outwardly.

4. The support and packoff assembly of claim 3 wherein the connection means includes a plurality of bolts threaded in the slip bowl and extending through the packing ring and gland.

5. The support and packoff assembly of claim 3 wherein the slip bowl has an annular seal member in its outer periphery and one in its inner periphery, both of the type actuated by the pressure differential to be sealed against.
